SHIPPING CASE

Harold E. Rue and Elof Nordstrom, East Orange,
N. J., assignors to Hoffman Beverage Company,
Newark, N. J., a corporation of New Jersey

Application May 19, 1932, Serial No. 612,212

9 Claims. (Cl. 217—19)

This invention relates to shipping cases and has particular reference to a case for shipping bottled beverages or the like.

Shipping cases are handled roughly and when made of wood, as is usually the case, are frequently broken or split, so that they must be repaired and eventually are damaged beyond repair, so that they must be replaced. Also, bottle cases as usually constructed are shallower than the bottles so that the necks of the bottles project above the top edges of the cases and if the cases are stacked they necessarily rest upon the tops of the bottles in the next lower case. Inasmuch as the bottles are loosely held in the usual wooden cases, it is apparent that but few cases can be stacked safely, since the resulting stack is insecure and likely to tip over if jarred. This loose packing of the bottles in the cases also results in rattling of the bottles and not infrequently in breakage when the cases are roughly handled or jarred while being transported in trucks or the like. In addition to these objections, the usual wooden cases are unsanitary, occupy more space than their contents warrant, and are not readily handled because only two small hand-holes are provided in the small ends of the case, which are not always accessible. It is accordingly highly desirable to provide a bottle shipping case which is sufficiently rugged to withstand the severe usage to which it is put, more compact and more easily handled than the usual wooden case, and one which holds the bottles securely against rattling and breakage and in such a way that the cases may be safely stacked one above the other to facilitate transportation.

In accordance with the present invention, a shipping case is provided in which all of the aforementioned desirable advantages obtain and which is constructed of metal and wood in a simple and inexpensive manner. More particularly, the case comprises a fabricated metal frame to which the wooden base is assembled in a novel manner and which is adapted to contain a removable liner and a bottle separator of cardboard or other similar material. With this construction, the bottles are closely packed in substantial engagement, except for the thickness of the cardboard walls of the separator extending between the bottles, whereby the entire group of bottles in the case are confined to a small space, form a substantially rigid mass, and are protected against breakage because they cannot rattle or strike against each other or against the case. Inasmuch as the bottles are rigidly and securely held in the cases, the cases may be safely stacked one

above the other and the underside of each case is provided with recesses for receiving the tops of the bottles in the case beneath, so that stacking is facilitated and the rigidity of the stack is increased. Accordingly, both the small size of the case and the stacking advantages permit more than the usual number of cases to be packed and transported in a truck having limited space. The cardboard liner is removable and preferably bears advertising material and does not interfere with the handling of the case but, on the contrary, it terminates below the upper rail of the metal frame so that the case may be readily grasped at any point around its periphery, this upper rail also being spaced from the adjacent bottles to facilitate handling of the case.

The case may be readily sterilized after removal of the liner and separator, and when a new liner and separator are inserted, it has a fresh and clean appearance which permits the entire case and contents to be usable for display purposes.

Other advantages of the invention will become apparent upon reference to the accompanying drawing, in which:

Figure 1 is a perspective view of the new shipping case of this invention without liner and separator; 25

Figure 2 is a transverse section thereof as seen along the line 2—2 of Fig. 3; 30

Figure 3 is a longitudinal section thereof as seen along the line 3—3 of Fig. 2; 35

Figure 4 illustrates the bottle separator in perspective;

Figure 5 illustrates the liner in perspective; 40

Figures 6 and 7 illustrate two steps employed in assembling the new case; and

Figure 8 is a partial view of the bottom of the case showing the manner in which the bottom members are secured together. 45

In this drawing, numeral 10 designates the fabricated metal frame of the new shipping case, which is preferably formed of relatively heavy gauge wire and is welded together. The frame 10 includes an upper rail 11, comprising a piece of wire bent into generally rectangular shape with its ends secured together by welding or the like. This upper rail 11 is supported by four U-shaped wire elements, the end elements being designated 12 and the side elements being designated 13. The upper rail 11 is preferably spot-welded to the horizontal upper portions of the elements 12 and 13, preferably by three or four spots W as indicated in Figs. 3 and 6. The end and side elements 12 and 13 are further secured together by two horizontal wire rails 14 and 15, which are of the 50

same size and shape as the upper rail 11. The legs of the side and end elements 12 and 13 are secured to each of the horizontal rails 14 and 15 by spot welding. While wire is preferred for fabricating the frame 10, strap or strip metal or the like may be employed with equal facility. The frame 10 is preferably galvanized or otherwise coated to prevent rusting.

As indicated in Figs. 1, 2, 6 and 7, the lower ends of the side elements 13 of the frame 10 are turned inwardly to form the horizontal extensions 16, while the lower ends of the end elements 12 terminate a short distance above the common plane of the extensions 16 of the side elements 13, the purpose of which will be described later.

The base of the new case preferably comprises three wooden members or boards 17, 18 and 19, of appreciable thickness and slightly less in combined width than the width of the fabricated frame 10, so that when the base members or boards 17, 18 and 19, are assembled, spaces appear between the adjacent members. The outer corners of the outer base members 17 and 19 are rounded as indicated in Fig. 1 and their outer edges are provided with spaced lateral sockets 20 adapted to accommodate the extensions 16 of the side elements 13 of the fabricated frame 10. These sockets 20 communicate with vertical grooves 21 in the outer edges of the members 17 and 19, in which the vertical portions of the side elements 13 adjacent their extensions 16 are adapted to lodge.

The ends of the base members 17, 18 and 19, are secured together in properly spaced relation by metal cleats 22 having the tongues 23 and 24 at their ends and the central tongue 25. These tongues 23, 24 and 25, serve to hold the cleat 22 and the base members 17, 18 and 19 in position while the nails 26 are being driven into the ends of the base members 17, 18 and 19. The nail holes in the cleats 22 are countersunk so that the heads of the nails 26 lie flush with the outer surfaces of the cleats 22.

Removably inserted within the fabricated frame 10 and resting on the base 17-18-19, is a liner 27, shown in perspective in Fig. 5. This liner preferably comprises a strip of cardboard, the ends of which are provided with interlocking tongues 28 so that it may be secured in shape when folded. The dimensions of the liner are such that it fits closely within the rails 14 and 15 and is high enough to extend slightly above the centre rail 14. It accordingly does not interfere with the upper rail 11 which is free to be grasped at any point on its periphery. This liner preferably bears advertising or identifying material which is visible through the open side of the fabricated frame 10 when the liner is in position within the latter, as indicated in Fig. 3. While a cardboard liner 27 is preferred, it may be made of sheet metal, fibre, plywood or other suitable material.

Removably inserted within the liner 27 and resting upon the base 17-18-19, is the separator 29 which comprises a plurality of interlocking strips of cardboard which are spaced apart the appropriate distance to accommodate the bottles or other merchandise adapted to be inserted in the cells formed within the separator 29. The cells are of such size that adjacent bottles engage each other except for the separating wall of the separator, so that the bottles brace each other.

In assembling the new shipping case of this invention, the frame 10 is fabricated in the manner described. The two outer base members or boards 17 and 19 are placed closely together in

parallel relation on a table or other flat surface, as indicated in Fig. 6, and the frame 10 is placed on them in such a way that the lower ends of the end members 12 rest upon the upper surfaces of the corresponding base members 17 and 19. The spacing between the lower ends of the end members 12 and the extensions 16 of the side members 13 is such that the extensions 16 and the corresponding sockets 20 in the base members 17 and 19 lie in the same plane when the frame 10 is placed on the base members 17 and 19 in the manner shown. It is therefore only necessary for the assembler to push the base members 17 and 19 outwardly, so that the extensions 16 are inserted in the corresponding sockets 20, and the lower ends of the side members 13 lie flush within the slots 21. This step is illustrated in Fig. 7.

Then the center base member 18 is placed and properly centered in the space between base members 17 and 19 and the three base members are temporarily held in this position by cleats 22, which are placed across the ends of the three members and then struck with a hammer or the like to drive the tongues 23, 24, and 25 thereof into the wood of these members. The cleats 22 accordingly fix the base members in proper position while the nails 26 are driven through the nail holes in the cleats to finish the assembling of the new shipping case.

The engagement of the lower ends of end members 12 with the upper surfaces of base members 17 and 19 also aids the lateral extensions 16 of the side members 13 in holding the base members 17 and 19 flatwise in the same plane, as is illustrated in Figures 1, 2 and 7. This arrangement prevents buckling of the base in the event that the end cleats 22 should become loosened because of heavy service.

The liner 27 is then folded into shape and placed within the case 10 and the separator 29 is inserted within the liner 27. As aforementioned, the cells in the separator 29 are of such dimension that they closely accommodate the product which it is intended to pack in the case. For example, if the case is to contain beverage bottles as indicated in Fig. 2, the bottles are mutually tangent except for the thickness of the intervening web of cardboard of the separator 29. The interior of the case between the horizontal rails 14 and 15 of the frame is also of such dimension as to closely accommodate the rows of bottles without looseness. The twelve bottles which the particular case illustrated and described is adapted to contain, are accordingly held rigidly within the casing and form a substantially rigid mass which cannot rattle and is not loose in the sense that bottles are usually loose in the ordinary wooden cases.

Aligned with the centers of the bottles which are packed within the casing, and located on the underside of the base member 17, 18 and 19, are recesses 30, each of such dimension as to accommodate the cap of a bottle placed therein from the underside. These recesses 30 are so arranged as to receive the caps of the bottles in the case below when the cases are stacked one above the other. Because the bottles are packed tightly and are aligned by recesses 30, a stack of cases containing bottles forms a rigid column and cannot be readily displaced or tipped over. Because of this arrangement many more cases of bottles may be carried safely in delivery trucks and the like without liability of breakage. The recesses 30 also closely confine the caps of the

bottles of the case below so that there is practically no movement between the caps and the base resting thereon. Consequently, there can be no abrasion or marring of the caps.

5 It will be seen that the upper rail 11 of the frame 10 is spaced a substantial distance from the adjacent bottles because of the inward curve of the necks of the bottles, so that rail 11 forms a convenient handle whereby the case may be lifted 10 and handled. The horizontal portions of end and side members 12 and 13 are located in the plane of the upper rail 11 so that a wide handle, which is more comfortable to handle and which will not cut the hands, is formed. Because the 15 bottles are packed very closely together and, because the cardboard of the separators 29 is relatively thin and, because the wire forming the frame 10 is relatively thin, the case is compact and occupies much less space than the usual 20 wooden shipping case. Also, the case may be altered in appearance for display purposes simply by replacing used liners with new liners of different color and appearance; it may be sterilized by immersing the entire case in a sterilizing bath 25 after removing the liner and separator; it may be readily assembled by unskilled workmen, and has a much longer life than the usual wooden cases and requires little or no repair. Also, the wooden 30 base of the new case with its rounded corners presents a smooth surface to conveyors, floors and the like, so that the movement of the case is facilitated and splitting and breakage are reduced. The wooden base also minimizes the noise of handling the case and may be stained pleasing colors, 35 painted or impregnated with preservation material to resist moisture and the action of sterilizing solutions in which the case is immersed and otherwise treated or decorated to suit requirements.

40 We claim:

1. In a bottle shipping case, the combination of a fabricated wire having an upper horizontal hand rail extending laterally from the adjacent bottles, a base for the frame, a removable liner 45 within the frame resting on the base and spaced from the hand rail, and a removable bottle separator within the liner.

2. In a shipping case, the combination of a substantially rectangular strip metal frame including verticals, the lower ends of the verticals of two opposite sides of the frame being turned substantially horizontally inwardly, the lower ends of the verticals of the remaining opposite sides of the frame lying above the plane of the 55 said horizontally inwardly turned lower ends of the said two opposite sides of the frame, and a base supported by the said horizontally inwardly turned lower ends of the said two opposite sides of the frame and engaged on its upper surface by the 60 said lower ends of the verticals of the said remaining opposite sides of the frame.

3. In a shipping case, the combination of a substantially rectangular strip metal frame including verticals, the lower ends of the verticals of two opposite sides of the frame being turned substantially horizontally inwardly, the lower ends of the verticals of the remaining opposite sides of the frame lying above the plane of the 65 said horizontally inwardly turned lower ends of the said two opposite sides of the frame, and a base having transverse recesses for receiving the said horizontally inwardly turned lower ends of the said two opposite sides of the frame and en-

gaged on its upper surface by the said lower ends of the verticals of the said remaining opposite sides of the frame.

4. In a shipping case, the combination of a substantially rectangular strip metal frame including verticals, the lower ends of the verticals of two opposite sides of the frame being turned substantially horizontally inwardly, the lower ends of the verticals of the remaining opposite sides of the frame lying above the plane of the 10 said horizontally inwardly turned lower ends of the said two opposite sides of the frame, and a base comprising at least two members each having transverse recesses aligned with the corresponding horizontally inwardly turned lower ends 15 of the said two opposite sides of the frame and engaged on their upper surfaces near their ends by the said lower ends of the verticals of the said remaining opposite sides of the frame.

5. In a shipping case, the combination of a 20 metal frame having inward extensions on its lower end on two opposite sides, a plurality of base members, the sides of the opposite base members having transverse recesses for the reception 25 of the inward extensions of the frame, the ends of the frame resting on the top of the base members, and means for securing the base members to each other.

6. In a shipping case, the combination of a fabricated steel wire frame including vertical elements, the vertical elements on two opposite sides being turned inwardly at their lower ends, a plurality of base members, the sides of the outside base members having transverse recesses for receiving the inwardly turned ends of said vertical 30 elements of the sides of the frame, means on the 35 ends of the frame for engaging the top of the base members, and means for securing the base members to each other.

7. In a shipping case, the combination of a rectangular metal frame comprising horizontal and vertical strips, the vertical strips on two opposite sides of the frame having inwardly turned ends, a base comprising a plurality of members, the sides of the outside base members having transverse recesses to receive the corresponding inwardly turned ends of said vertical strips, the vertical strips of the end sections of the frame resting on 40 the top of the base members, and means for securing the base members to each other.

8. In a shipping case, the combination of a substantially rectangular frame, a base comprising a plurality of sections, means on two opposite sides of said frame for securing said frame to said base, the ends of the frame being unsecured to said base and resting on the upper surface thereof, and means for securing the sections of the base to each other.

9. In a shipping case, the combination of a frame open at the top and bottom and comprising inverted U-shaped wire side and end members and ring shaped wire rails secured in spaced horizontal relation to each of the side members, a base comprising a plurality of sections closing the open bottom of said frame, the U-shaped side 60 members of said frame being secured to the outside sections of said base, the U-shaped end members of said frame being unsecured to said base and means for securing the sections of said base 65 to each other.
